G. F. KEIL

TAMPER FOOT

Filed Sept. 8, 1925

UNITED STATES PATENT OFFICE.

GEORGE F. KEIL, OF EUGENE, OREGON.

TAMPER FOOT.

Application filed September 8, 1925. Serial No. 54,900.

To all whom it may concern:

Be it hereby known that I, GEORGE F. KEIL, a citizen of the United States, and a resident of Eugene, in the county of Lane 5 and State of Oregon, have invented a new and useful Tamper Foot, of which the following is a specification.

This invention relates generally to the art of making concrete drain tile, sewer pipe 10 and culvert pipe, and particularly to a special form of tamper foot.

The first object of this invention is to provide a special form of tamping foot which will permit heavier and faster feeding of 15 the aggregate.

The second object is to permit harder tamping without danger of breaking the tamping sticks.

The third object is to so construct the 20 tamper foot that it will not catch on the reinforcing wires and thereby break same and cause a loss of material and delay in operation.

The fourth object is to render the tamping 25 more uniform throughout the length of the pipe being formed.

The fifth object is to prevent the tamper foot from throwing the mix up ahead of the tamper as it moves instead of drawing it 30 under, as is the case with this device.

The sixth and ultimate object is to increase the net production from a machine using this type of device, which increase, when measured over long periods, amounts 35 to approximately twenty per cent.

I accomplish these results in the manner set forth in the following specification as 40 illustrated in the accompanying drawing, in which:

Figure 1 is a side elevation of the type 45 of machine with which this device is used having its upper portion broken away in section to show the tamper foot in use when reinforcing wires are being used. Figure

2 is a side elevation of the tamper foot 50 with its stick broken off and showing the manner in which the mix is drawn under the foot instead of piling up in front of same. Figure 3 is an elevation of the tamper foot of which Figure 4 is a horizontal section taken along the line 4-4 in Figure 2.

Similar numbers of reference refer to the same parts throughout the several views.

Referring in detail to the drawing: In

order to better illustrate the use of this device and the advantages arising therefrom, there is indicated the usual turntable 10 upon which is placed a cylindrical mold 11. A stationary core 12 is placed inside of the 60 mold 11 and a chute 13 is employed to feed aggregate 14 into the space between the mold 11 and the core 12. Vertical reinforcing wires 15 and horizontal reinforcing wires 16 are employed when the pipe being 65 formed is used for special purposes such as culverts, etc.

In this type of machine are employed one or more tamper sticks 17, on the lower end of each of which is secured a tamper foot. 70 It is to this element that this particular invention refers. This tamper foot is ordinarily a U-shaped shoe fastened by any convenient means to the bottom of the stick 17.

In this construction I prefer to provide the 75 foot with a pair of upturned arms 18 and 19 which are secured to the stick 17 by means of the screws 20. The arm 19 is preferably flush with its side of the stick. The under side of the foot is provided with 80 a sloping face 21 having a rounded heel 22 and a somewhat square toe 23 which projects past the rearward side of the shoe.

It is preferable to curve the entire shoe, as 85 shown in Figure 4, so that it will better accommodate itself to the shape of the pipe being tamped. It is also desirable to have a number of different widths of tamper feet to take care of the different thicknesses of pipe wall and to permit their use with 90 reinforcing wires.

Machines of the character above described are provided with a suitable reciprocating mechanism, such as an eccentric, by means of which the stick 17 can be moved vertically 95 at a speed of approximately four hundred strokes per minute. They are also provided with a suitable friction holder for the sticks to insure the desired degree of tamping.

These mechanisms are not illustrated as 100 their use is common in the art and are well understood by users of this class of machines.

The operation of the device is as follows: Concrete is fed into the mold through the 105 chute 13 and the mold is rotated. If the pipes are to be reinforced the wires 15 and 16 are first put into place and the tamping stick 17 is inserted on each side of the wires. As the mold is rotated the loose aggregate 110

24 passes under the heel 22 of the tamper foot and is gradually but rapidly tamped to the depth of the toe 23.

Owing to the shape of the tamper foot it is impossible for the foot to pick up or pile up the loose aggregate in case it is fed too rapidly, or the mold is rotated too rapidly within the limits, of course, at which material is fed into such machines. When the ordinary foot is employed a surplus of mix in front of the stick will be almost certain to cause the stick to break, and will necessitate a shut-down of the machine for the purpose of installing a new stick and removing the partially formed pipe. This is also true when the tamper foot catches on the reinforcing wires, not only causing a waste of material but also a considerable loss of operating time.

In order to secure a more perfectly uniform tamping of the concrete it is preferable to serrate the sole of the foot, as indicated in Figure 2. This eliminates entirely any imperfectly tamped areas. The number and shape of the serration can, of course, be varied at will.

I am aware that tamper feet have long been employed in concrete pipe construction; I therefore do not intend to cover same broadly, but I do intend to cover all such forms and modifications of same as fall fairly within the appended claims.

I claim:

1. A tamper foot for concrete pipe machines having means for attaching same to

a tamper stick; an undercut front heel member; and a downwardly sloping rearwardly projecting toe member.

2. A tamper foot for concrete pipe machines having, in combination, a pair of tamper stick attachment arms and having the under side of the foot sloping in one direction, said under portion having an undercut rounded heel at its upper end and a projecting toe at its lower end.

3. A tamper foot for concrete pipe machines consisting of a downturned curved foot member having a sloping sole with a raised rounded heel and a downwardly projecting toe extending beyond the rear of said foot.

4. A tamper foot for concrete pipe machines having an upright stick attachment member and having a horizontally curved and downwardly sloping foot having its lowermost point extending beyond its stick attachment member and having its uppermost portion curved upwardly to one side of the stick attachment member.

5. A tamper foot for concrete pipe machines having an upturned stick attachment member consisting of two spaced arms adapted to receive a tamper stick between same and having screw holes formed through said arms, said foot having a laterally curved serrated sole member, including a rounded heel, under one end of said arms; and a toe at the lower end of said sole projecting beyond the opposite arm member.

GEORGE F. KEIL.
